UNITED STATES PATENT OFFICE.

SVEN N. HOLM, OF DORCHESTER, MASSACHUSETTS.

MIXING-VALVE

1,384,132.

Specification of Letters Patent. Patented July 12, 1921.

Application filed July 5, 1919. Serial No. 308,784.

To all whom it may concern:

Be it known that I, SVEN N. HOLM, a citizen of the United States, residing at Dorchester, county of Suffolk, Commonwealth of Massachusetts, have invented certain new and useful Improvements in Mixing-Valves, of which the following is a specification.

This invention relates to mixing valves, and particularly to a fixture for mixing hot and cold water for use in bath tubs, wash basins, shower baths, and the like.

In devices of this class as usually constructed, no provision other than the usual shut-off valves at the tub and shower connections is made for controlling the water discharge from the mixing chamber. My invention aims to provide simple and effective structure for delivering hot or cold water or a mixture thereof, for indicating the exact temperature of the mixture or either of the constituents, and for selectively controlling the discharge of the mixture, or either of its constituents, to a tub or shower connection. My invention provides in a single valve structure a combination intake and discharge control so constructed and arranged that the operation shutting off the delivery to the tub, for example, will automatically open the delivery to the shower connection, and vice versa, thus dispensing with the necessity for the usual shut-off valves at the tub and shower connections.

The construction and operation of my device is disclosed in the following specification and drawings, throughout which corresponding reference numerals are used to indicate corresponding parts. In the drawings:

Figures I and II are side and front elevations, respectively, of a mixing valve in accordance with my invention.

Fig. III is a longitudinal section thereof.

Fig. IV is a vertical section on the line IV-IV of Fig. I.

Fig. V is a view looking down into the mixing chamber, the cover and spindle for the intake valve being removed.

Fig. VI is a plan section through the mixing chamber, particularly illustrating the rotatable sleeve valve controlling the mixture discharge from the mixing chamber.

Fig. VII is a detail view of the intake valve and its seat, in top plan.

Fig. VIII is a cross section thereof.

Fig. IX is an elevation showing the parts set to permit adjustment of the sleeve valve.

Fig. X is a detail view particularly showing the ported sleeve valve.

Fig. XI is a plan view thereof.

Figs. XII and XIII are detail views of the valve spindle removed.

Fig. XIV is a detail view in plan and elevation of the notched setting nut which fixes the position of the ported sleeve valve, and

Fig. XV is a detail view in plan and elevation of the locking nut which co-operates with the setting nut.

I have indicated at 1 the bowl or mixing chamber of my valve. The mixing chamber 70 is constructed as a shell of generally cylindrical form providing a flat valve seat 2 through which are let spaced hot and cold water inlet ports 3 and 4, the shell at one side of said seat being extended, as indicated 75 at 5, and providing a hot water intake 6 and a cold water intake connection at 7. The inlets 6 and 7 provided by the walled extension 5 are separated from each other by a web 8. At the opposite side of the valve seat 80 2, the shell is provided with a tub connection 9 and a shower connection 11 oppositely arranged as to each other. The shower connection 11 may have an offset 10 opening into the mixing chamber and pierced to receive a thermometer 12, the mercury end of the thermometer being exposed directly to the mixture within the chamber 1 and the reading end extending upwardly for convenient observation and to some extent for 90 protection by the riser 13 threaded into connection 11.

Set through seat 2 is a threaded stud 14 upon which is rotatably mounted a disk valve 15 which is provided, as here shown, 95 with a single port 16 adapted to selectively lap ports 3 and 4 and of sufficient extent to simultaneously lap both of said ports. (See Fig. VII.)

The valve 15 may be rotated by any convenient mechanism to regulate the inlet of water into the mixing chamber. For the purposes of this application, I have shown the exposed face of the valve as provided with a squared head or facing 17 which is 105 adapted to be engaged by the correspondingly shaped wrench socket 18 of a rotatable valve spindle 19. The facing 17 may be cast upon the valve, and is so shown in the drawings, the valve being further ribbed as indicated at 20, Fig. VII, and the wrench socket 110 18 being kerfed as indicated at 21, Figs. XII

2
and XIII, to key with said ribs 20, whereby to insure positive transmission of the rotative tendency of the spindle to valve. The rotation of the valve in either direction may 5 be limited, as by trimming away a portion of its periphery, as indicated at 22, leaving stop shoulders 23 adapted to abut a fixed stop 24, here shown as a simple screw set through seat 2 and projecting into the arc of 10 travel of said shoulders. The free end of the spindle 19 may be squared to receive an operating handle 25 and an indicator 26 which travels over suitable markings 27 upon the outer face of a cover 28 threaded 15 into the open end of the mixing chamber 1, whereby to indicate the position of the disk valve 15.

In the construction as thus far described, 20 rotation of the disk valve 15, controls the intake of hot and cold water separately into the mixing chamber through ports 3 and 4, according to which port the port 16 or valve 15 is turned into registry with, or where a mixture is desired, whether port 16 laps both 25 ports 3 and 4. By arranging the intakes 6 and 7 for the hot and cold water in the extension 5 of the bowl 1 at one side of valve seat 2, the entire internal area of the bowl is 30 left uninterrupted and the water entrance into the bowl is directly closed by a face of the valve. When the valve 15 is opened, the water flows through port 16 thereof into the mixing chamber and discharges therefrom through either tub connection 9 or shower 35 connection 11, according to the position of a rotative discharge valve.

The valve controlling the discharge of the hot or cold water, or mixture thereof, from the mixing chamber 1 is here shown as a 40 ported sleeve or shell comprising a relatively flat surmounting head 29 and an annular rim portion 30. The head 29 is ported as indicated at 31, Fig. XI, and the rim 30 as indicated at 32, Fig. XII, ports 31 permitting 45 passage of the water through the valve to the thermometer and ports 32, permitting discharge of the water into tub or shower connection, according to the position of said ports 32 with relation to the connections 9 or 11.

Extending from the head 29 is a tubular stem 33 upon which the cover 28 is mounted and through which spindle 19 extends and is journaled in a stuffing box nut 34 threaded 55 on the outer threaded end 33¹ of said stem 33. The cover 28 is made water-tight on said stem by a stuffing box 35, the cover 28 being reduced and externally threaded as indicated at 36 to receive the stuffing box 60 collar or nut 37. Said nut as here shown is provided with a series of radially disposed peripheral kerfs 38 with which is adapted to engage an opposing series of lugs 39 formed on a locking nut 40 applied to the 65 threads 33¹ of stem 33 beyond nut 37. The

tongue and groove connection at 38-39 is normally held, as by a coiled spring 41 confined about the stem 33, between a shoulder 33^a thereon and the internal face of the cover 28. When interengaged, nuts 37 and 40 prevent rotation of stem 33. The spring 41 also tends to hold the valve to its seat against the lifting effect of the water entering the mixing chamber through ports 4 and 3. By drawing nut 40 outwardly along 75 the stem 33 a sufficient distance to clear lugs 39 from slots 38, as indicated in Fig. IX, said stem may be turned to bring one or the other of its ports 32 into or out of registry with tub connection 9 or shower connection 11, thus regulating the discharge of water from the mixing chamber. The relation of the kerfs 38 to the ports 32 is such that a partial turn of the stem to move the lugs 39 from one set of kerfs to another 85 carries a port 32 out of registry with the tub connection 9, for example, closing that connection, and brings another port 32 into registry with the shower connection, opening that connection. 90

It will thus be seen that the water discharge through outlets 9 or 11 of the mixing chamber depends upon the position of the ports 32 in sleeve valve 30 relative to said outlets, and that a single operation of 95 the said sleeve valve automatically opens one of said outlets and closes the other. By this construction, I avoid the necessity for individual shut-offs in the tub and shower connections. 100

Various modifications in the form and construction of my device may obviously be made, all without departing from the spirit of my invention if within the limits of the appended claims. 105

What I therefore claim and desire to secure by Letters Patent is:

1. In a mixing fixture, a mixing chamber having independent pairs of inlet and discharge openings, and independent valves mounted coaxially within said mixing chamber and controlling said openings. 110

2. In a mixing fixture, a mixing chamber having a pair of inlet openings and a pair of spaced independent discharge openings, 115 a valve controlling said inlet openings and a single valve mounted within said mixing chamber and simultaneously controlling both of said discharge openings.

3. In a mixing fixture, a mixing chamber having a pair of inlet openings and a pair of spaced independent discharge openings, 120 a valve controlling said inlet openings and a single valve mounted within said mixing chamber and simultaneously controlling both of said discharge openings, 125 consisting of a rotatable shell having spaced ports adapted to be brought into and out of registry with said discharge openings.

4. In a mixing fixture, a mixing chamber 130

- having a pair of inlet openings and a pair of spaced independent discharge openings, a valve controlling said inlet openings, a control for said discharge opening comprising a valve rotatably mounted within said mixing chamber and having ports adapted to be selectively brought into and out of registry with said discharge openings, and spring-tensioned relatively separable interlocking devices for permitting and preventing rotation of said discharge valve to vary the positioning of the ports thereof relative to said discharge openings.
5. In a mixing fixture, a mixing chamber having a pair of inlet openings and having independent discharge openings, a valve controlling said inlet opening, a control for said discharge openings mounted within said mixing chamber and comprising a stem provided sleeve valve having spaced ports adapted to be selectively brought into and out of registry with said discharge openings, a relatively fixed and a relatively movable locking piece on said stem normally interengaged to prevent operation of said sleeve valve and separable to permit operation thereof, and a spring normally tending to maintain said locking pieces interengaged.
10. In a mixing fixture, a mixing chamber having a pair of inlet openings and having independent discharge openings, a valve controlling said inlet opening, a control for said discharge openings mounted within said mixing chamber and comprising a cup-shaped sleeve valve having a stem-provided head and a port-provided annular rim, the ports of said rim being adapted to be selectively brought into and out of registry with said discharge openings by rotation of the sleeve valve, a relatively fixed and a relatively movable locking piece on said stem having interengaging tongues and grooves, a coil spring about said stem normally tending to maintain said locking pieces interengaged, said stem being tubular, and an operating spindle for said inlet control extending through said stem and exposed beyond the end thereof for hand operation.
15. In a mixing fixture, a mixing chamber having a pair of inlet openings and a discharge connection, an inlet control valve and a discharge control valve mounted within said chamber, said discharge connection having an offset opening into said mixing chamber, and said discharge control valve
- having a port adjacent said offset and having a port adapted to register with said discharge connection, and a thermometer mounted in said offset with its mercury end extending into said mixing chamber and exposed to the mixture passing through said port.
8. In a mixing fixture, a mixing chamber having a pair of inlet openings and a pair of discharge openings, a valve mounted within said chamber and controlling said inlet openings, and a second valve mounted within said chamber in coaxial relation to said first-named valve and controlling said discharge openings.
9. In a mixing fixture, a mixing chamber having a pair of inlet openings, and a pair of discharge openings, a valve mounted within said chamber and controlling said inlet openings, and a second valve mounted within said chamber and having ports adapted to be selectively brought into registry with said discharge openings.
10. In a mixing fixture, a mixing chamber having a pair of inlet openings and a pair of discharge openings, a valve mounted within said chamber and controlling said inlet openings, and a second valve mounted within said chamber and consisting of a cup-shaped sleeve having a stem-provided head by means of which said sleeve valve may be rotated and having a port-provided rim, the ports of said rim being adapted to be selectively brought into and out of registry with said discharge openings by rotation of the sleeve valve.
11. In a mixing fixture, a mixing chamber having a pair of inlet openings, and a pair of discharge openings, a valve mounted in said chamber and controlling said inlet openings, and a second valve mounted within said chamber and having a pair of ports movable into and out of registry with said discharge openings whereby upon operation of said second named valve one of said discharge openings is automatically opened and the other discharge opening is automatically closed.
50. In testimony whereof I affix my signature in presence of two witnesses.
